UNITED STATES PATENT OFFICE.

HOWARD MILTON JOHNSTON, OF TORONTO, ONTARIO, CANADA, ASSIGNOR TO MASSEY-HARRIS COMPANY, LIMITED, OF TORONTO, CANADA.

SHEAF CARRIER FOR BINDERS.

Application filed August 23, 1922. Serial No. 584,876.

To all whom it may concern:

Be it known that I, HOWARD M. JOHNSTON, of the city of Toronto, in the county of York, Province of Ontario, Canada, a subject of the King of Great Britain, have invented certain new and useful Improvements in Sheaf Carriers for Binders, of which the following is a specification.

This invention relates to attachments for harvester binders adapted to catch and temporarily hold a plurality of sheaves as they are discharged from the binder deck, and my object is to devise a carrier which will clear the ground under any working conditions of the machine, which will employ a minimum number of fingers and yet will catch any sheaf discharged and during any longitudinal adjustment of the binder deck, which is particularly adapted to carry sheaves when the binder is turning corners to avoid the sheaves being discharged where they are liable to be trampled on at the next round of the machine, and which is useful also on the straight where a tendency exists to discharge sheaves at irregular distances.

I attain my object by means of the construction hereinafter described and illustrated in the accompanying drawings in which—

30 Fig. 1 is an end elevation in outline of a harvester binder provided with my improved sheaf carrier indicated by dotted lines in its sheaf receiving position and in full lines in its depending position;

35 Fig. 2 a plan view of parts of the carrier mechanism in its depending position and on a larger scale;

40 Fig. 3 a plan view of part of the same, partly in section and showing the fingers in their receiving position;

45 Fig. 4 a detail in end elevation of Fig. 2 of the same showing one of the fingers in a depending position; and

Fig. 5 a similar view of Fig. 3, the finger being shown in a sheaf receiving position.

In the drawings like numerals of reference indicate corresponding parts in the different figures.

1 is the fixed frame of a harvester binder and 2 the frame carrying the knotter mechanism, which is adjustable back and forth to suit the length of the grain being cut. This arrangement, being common in the art, is not illustrated in detail.

50 55 On the frame 2 is journalled a shaft 3.

This shaft is preferably square to facilitate the mounting of the fingers 4 thereon. It is therefore provided with sleeves 5 and 5^A which form journals rotatable in bearings formed in the frame 2. At one end of the sleeve 5 is formed a collar 6, which engages the outer side of the bearing. At the inner side the sleeve is positioned on the bearing by the washer 7 held in place by the pin 8 driven through the shaft. At the other end the sleeve 5^A is externally cylindrical and has an arm 9 formed thereon by means of which the shaft may be rocked. For the purpose of rocking the shaft I employ a foot lever 10 of ordinary type, which is journalled on the frame of the harvester binder and is connected by means of a connecting rod 11 to the bell crank lever 12, also fulcrumed on the frame of the harvester binder. This bell crank lever is connected by means of the connecting rod 13 with the rock arm 9.

The fingers 4 are curved as shown particularly in Figs. 1 and 5 so that when they are extended horizontally to receive sheaves, the outer ends extend upwardly. Each finger is journalled on an axis transverse of the shaft 4 in a bearing 14 secured to the shaft.

The inner end of each finger is bent substantially at right angles to form a crank arm 15, this crank arm, however, preferably not lying in the same vertical plane as the rest of the finger when the finger is extended as shown in Figs. 1 and 5. This angular position of the crank arm relative to the rest of the finger is best seen in Fig. 2, the purpose of the arrangement being to have the inner ends of the crank arms well away from the shaft whether the fingers be in the position shown in Figs. 4 or 5. The ends of the crank arms are bent substantially at right angles in a direction parallel to the axes of the bearings of the fingers, and with these ends is pivotally connected the connecting rod 16. It is evident that by actuating the connecting rod in the direction of its length that the fingers may be simultaneously swung on their journals.

It is desired that a rearward swing of the finger ends shall take place simultaneously with the dropping of the fingers from the position shown in Fig. 5 to the position shown in Fig. 4. This is effected in the following manner. Preferably integral with

the sleeve 5 at the left hand side of Fig. 2 is formed a cam 17. This cam is engaged by a projection 18 on the connecting rod 16. When the shaft is swung up from the position shown in Figs. 2 and 4 to the position shown in Fig. 5, the projection 18 rides down the cam 17 and the connecting rod is moved in the direction of the arrow in Fig. 2, thus turning the fingers on their journals to bring the points thereof, which have been directed rearwardly, to a position in which they are directed upwardly as shown in dotted lines in Fig. 1 and in full lines in Fig. 5. When the shaft is rocked in the reverse direction to bring the fingers to the position shown in full lines in Fig. 1, and in Figs. 2 and 4, a coil spring 19 connected at one end to the connecting rod and at the other to the shaft moves the connecting rod in the reverse direction to that indicated by arrow in Fig. 2 and causes the fingers to swing so that their points are rearwardly directed.

To take some of the strain off the bearings 25 14, I form on each bearing an arc-shaped guide 20 which overlies the adjacent crank arm 15 and is contacted thereby.

What I claim as my invention is:—

1. The combination with a harvester binder of a shaft journalled thereon adjacent the outer edge of the binder deck; a plurality of curved fingers having journals journalled on said shaft on axes transverse of the shaft; means for rocking the shaft to swing the fingers up and down; crank arms formed on the ends of the journals of the fingers; a connecting rod pivotally connected with said crank arms; a projection on said rod; a stationary cam with which said projection engages whereby the crank arms are moved simultaneously with the rocking of the shaft.

2. The combination with a harvester binder of a shaft journalled thereon adjacent the outer edge of the binder deck; a plurality of curved fingers having journals journalled on said shaft on axes transverse of the shaft; means for rocking the shaft to swing the fingers up and down; crank arms

formed on the ends of the journals of the fingers; a connecting rod pivotally connect- 50 ed with said crank arms; a projection on said rod; and a stationary cam with which said projection engages whereby the rock arms are moved simultaneously with the 55 rocking of the shaft.

3. The combination with a harvester binder of a shaft journalled thereon adjacent the outer edge of the binder deck; a plurality of curved fingers having journals journalled on said shaft on axes transverse of the shaft; means for rocking the shaft to swing the fingers up and down; crank arms formed on the ends of the journals of the fingers; guides connected to the shaft engageable by the crank arms to reduce the 60 strain on the journals of the fingers; a connecting rod pivotally connected with said crank arms; and means for longitudinally moving said connecting rod simultaneously with the rocking of the shaft. 70

4. The combination with a harvester binder of a shaft journalled thereon adjacent the outer edge of the binder deck; a plurality of curved fingers having journals journalled on said shaft on axes transverse 75 of the shaft; means for rocking the shaft to swing the fingers up and down; crank arms formed on the ends of the journals of the fingers; a connecting rod pivotally connected with said crank arms; a projection on said rod; a stationary cam with which said projection engages whereby the crank arms are moved simultaneously with the rocking of the shaft, the said cam tending only to actuate the rock arms to turn the points of the 80 fingers upwardly as the fingers are swung up; and a spring tending to actuate the crank arms in the opposite direction to turn the points of the teeth rearwardly. 85

Signed at city of Toronto, county of York, 90
this 3rd day of August, 1922.

HOWARD MILTON JOHNSTON.
